UNITED STATES PATENT OFFICE.

EVAN H. WADE AND JOHN L. NICHOLSON, OF CHICAGO, ILLINOIS,
ASSIGNORS TO AMERICAN LOCOMOTIVE EQUIPMENT CO., OF
CHICAGO, ILLINOIS, A CORPORATION OF ILLINOIS.

LOCOMOTIVE-FURNACE.

No. 820,451.

Specification of Letters Patent.

Patented May 15, 1906.

Application filed September 13, 1904. Serial No. 224,306.

To all whom it may concern:

Be it known that we, EVAN H. WADE and JOHN L. NICHOLSON, citizens of the United States, residing at Chicago, in the county of Cook and State of Illinois, have invented a certain new, useful, and Improved Locomotive-Furnace, of which the following is a specification.

Our invention relates to improvements in furnaces, and has special reference to locomotive-boiler furnaces.

This invention is a modification of that which is shown and described in a companion application executed by us September 3, 1904, and in which we have disclosed a boiler-furnace that is equipped with arches which extend from the front and rear walls of the furnace, said arches being provided with passages and deflectors so formed that air will be admitted to the fire-box and discharged downwardly from points near the inner end of the arches to maintain a barrier of air across the path of gases and products ascending from the fire to the combustion-chamber of the furnace.

The object of this invention is to provide a furnace characterized as above, but having arches which may be more readily placed in position or removed from the furnace; and a further object of our invention is to improve the construction of the front arches of locomotive-boiler furnaces with a view to facilitating access to the flue-sheet of the furnace when it is necessary to repair the flues of the boiler.

A further object of the invention is to modify and improve the front arch of the aforesaid application and adapt the same for employment in connection with arch-tubes and at the same time so construct the arch that it may occupy a high position in the furnace and yet not interfere with or close any of the boiler-flues. The specific object of the invention is to provide a furnace-arch that shall be composed of a few large bricks which may be easily separated even after a long period of use and exposure to heat.

Our invention consists generally in a furnace equipped with front and rear arches that contain air-channels and downwardly-inclined deflectors adapted to direct the admitted air toward the grate in converging streams, the arch which is adjacent to the

flue-sheet of the furnace being composed of bricks that are in substantially the same inclined plane and including middle bricks so constructed that the same may be readily removed, to provide an opening or gap in the arch through which the boiler-flues may be reached; and, further, our invention consists in a furnace that is equipped with an arch or arches composed of a plurality of refractory bricks with non-fusible material between them, whereby the fusing of the bricks is prevented, so that the arch may be taken down at any time without destroying the bricks; and, further, our invention consists in a front arch composed of a plurality of refractory bricks whereof the lower and middle brick is relatively depressed, both outer and middle bricks of the arch being provided with channels to communicate with air-entrance tubes at different elevations in the front water-leg of the boiler; and, further, our invention consists in a boiler-furnace provided with arch-tubes in combination with a front arch supported on said arch-tubes, and a rear arch below said arch-tubes, both said arches having air channels and deflectors, as above described; and, further, our invention consists in various details of construction and in combinations of parts, all as hereinafter described, and particularly pointed out in the claims.

The invention will be more readily understood by reference to the accompanying drawings, forming a part of this specification, and in which—

Figure 1 is a vertical longitudinal section of a locomotive-furnace embodying our invention. Fig. 2 is an elevation of the rear end of a boiler. Fig. 3 is a compound sectional view, one-half thereof being on the line A A of Fig. 1 and the other half on the line B B of Fig. 1. Fig. 4 is a sectional view on the line C C of Fig. 1. Fig. 5 is a sectional view on the line D D of Fig. 1, showing the upper middle brick of the arch removed. Fig. 6 is a sectional view on the line E E of Fig. 1. Fig. 7 is a horizontal sectional view on the irregular sectional line F F of Fig. 1 viewed in the direction of the arrows. Fig. 8 is a sectional view of the inner end of the terminal bricks of the rear arch on the line G G of Fig. 1. Fig. 9 is a similar sectional view of the end of the terminal bricks of the front arch on the line H H of

Fig. 1, and Fig. 10 is a sectional view of a group of intermediate bricks in the rear arch on the line I I of Fig. 1.

As shown in the drawings, 2 represents the boiler - shell, which contains the furnaces, whereof 3 is the crown-sheet; 4 4, the side walls; 5, the rear wall; 6, the front wall or flue-sheet; 7, the grate, and 9 9 the usual arch-supporting water-tubes, which extend from the lower part of the front water-leg 10 to the upper part of the rear water-leg 10'. 11 11 are the boiler-flues, and 12 is the furnace-door.

The furnace-chamber contains two hollow arches composed of refractory bricks. The front arch rests upon the arch-tubes 9 and contains air-heating channels 13, the lower ends of which communicate with the air-thimbles, tubes, or hollow stay-bolts 14 in the front water-leg 10. The channels 13 open into the cavity 16 at the upper end of the arch, and said cavity is provided with an inclined or deflecting surface 17, the effect of which is to turn and project the heated air downwardly upon the fire and across the throat of the furnace. The novel features which distinguish the front arch from others will be described hereinafter. The rear arch is arranged below the upper rear ends of the arch-tubes 9, immediately above the furnace-door. The bricks composing the rear arch are preferably curved, arched against each other, and are supported by lugs 18 on the side walls of the furnace. Said rear arch has air-channels 13' and a cavity 16' communicating with air-tubes 14' in the rear water-leg. The rear arch has a deflecting-surface 17', and, as in the case of the front arch, the incoming air is projected therefrom upon the fire and across the throat. It should be here noted that the streams of air from the two arches converge upon a line above the fire and together form a complete air-barrier beneath the throat of the furnace. The gases and other fuel products which rise from the fire on the grate can only reach the furnace-throat and the combustion-chamber—the space above the arches—by passing through this air-barrier, and the effect is to enrich said gases and products with oxygen, thereby insuring completeness of combustion.

Aside from the described relations of the arches and the arch-tubes to provide the air-barrier, the particular novelty in this application resides in the construction of the front arch. It is well known that although the furnace-arches in present use are composed of a number of sections or bricks they cannot be taken down, brick by brick, after the furnace has once been used, because the bricks fuse together. Hence when it is necessary to reach the flue-sheet of the furnace the arch must be destroyed, with consequent waste of labor and material. The arch of our invention is composed of a number of

bricks, and in this regard is like other arches; but the middle bricks of our arch are made wedge shape, like unto a keystone, and between the several bricks we place a non-fusible material, such as silicon or asbestos 24, 7c which prevents the fusing of the joints, and as the bricks do not fuse the middle bricks may at any time be lifted out and set to one side, as shown in Fig. 5, to form a recess or 75 alley through the arch, thus permitting free access to the entire flue-sheet. Said arch is composed of several tiers of bricks 20, 21, and 22. The intermediate tiers 21 are identical, and the number used determines the height and length of the arch. The arch is flat in 80 cross-section—that is, it need not be curved like the rear arch, as it is supported on the arch-tubes 9. Upon viewing the arch from the end it will be seen that the inner ends of the outer bricks in each tier are beveled 85 and that the middle brick has the appearance of a keystone. Vertical joints between the bricks are thus avoided and the middle bricks are made easy to slip into place or to remove. We prefer that the middle bricks 90 shall be supported by the outer bricks and shall tend to thrust said bricks outwardly. The bottom and the intermediate bricks are provided with oval air-passages, (see Fig. 10,) while the terminal bricks have the cavities 95 16, containing the deflecting - surfaces 17. (See Fig. 9.) The non-fusible material—silicon or asbestos—between the bricks serves to close the joints and prevent leakage of air from the arch-channels. Thus we secure an 100 arch which is tight at all joints and yet one that may be easily taken down even after long use. If desired, the outer bricks of the arch may be permitted to fuse together—that is, the non-fusible material may be used 105 only in the middle brick-joints, said middle bricks being the only parts of our arch which need be removed when access to the boiler-flues is required. It will be observed that the air-supply tubes 14 for the front arch are 110 arranged in the front water-leg directly beneath the cylindrical portion of the boiler. It will also be seen that the boiler-flues are only slightly above the lower ends of the arch-tubes.

In most furnaces an arch of the thickness of ours if wholly above the arch - tubes would be too high to communicate with the middle air-tubes 14 and would also block or stop off the lower flues of the boiler. The air for the arch-channels may be supplied through tubes in the grate or through the sides of the fire-box; but to avoid closing the lower boiler-flues and to provide for the direct supply of air to the middle channels 13 of the arch we employ a lower tier of bricks 20, that conforms to the most convenient arrangement of the air-tubes 14. This arrangement is shown in Figs. 1 and 3, wherein it will be seen that the tubes 14 for the middle 130

channels 13 are considerably beneath the outer pairs of tubes 14 belonging to the channels in the outer bricks of the arch. The lower ends of the outer bottom bricks are relatively elevated, corresponding in position to the horizontal portion of the arch-tubes, while the bottom middle brick is relatively depressed. (See Figs. 1, 3, 5, and 6.) A portion of the middle brick hangs between the arch-tubes 9, 9, and the passages 13 therein are in substantial alinement with the passages in the upper bricks, descending to a point that is beneath the bottom of the cylindrical portion of the boiler, and in this way communication is established between the passages in the middle arch bricks and the lower pair of air-tubes 14. We prefer to taper the air-passages 13 in the middle brick of the bottom tier, as shown in Fig. 7; but said passages may take different forms. The tops of the middle bricks may be flat or crowned, as shown. It is obvious that numerous modifications of our invention will readily suggest themselves to one skilled in the art, and we therefore do not confine the invention to the specific constructions herein shown and described.

Having thus described our invention, we claim as new and desire to secure by Letters 30 Patent—

1. A locomotive-boiler having a furnace provided with arch-tubes connecting its front and rear water-legs, in combination with a front arch supported upon said arch-tubes, and a rear arch suitably supported beneath said arch-tubes, both said arches having passages for supplying heated air to the furnace and adapted to project the currents of air from each arch below the other and 40 hence across the opening or throat between said arches, substantially as described.

2. A locomotive-boiler having a furnace provided with arch-tubes connecting its front and rear water-legs, in combination 45 with a front arch supported upon said arch-tubes, and a rear arch suitably supported beneath said tubes, both said arches having air-passages communicating with the outer air and deflectors for projecting air-currents 50 from both arches across and beneath the opening between said arches, substantially as and for the purpose specified.

3. A locomotive-boiler having a furnace provided with arch-tubes that connect the 55 front and rear water-legs of the boiler, said furnace having a door, air-entrance tubes extending through the rear water-leg, an arch of refractory material arranged beneath said arch-tubes, said arch having passages communicating with said air-tubes, and also provided with a bottom cavity and a downwardly-inclined deflecting-surface, air-entrance tubes arranged in said front water-leg, beneath the cylindrical part of the boiler, 65 a front arch composed of refractory bricks

resting upon said arch-tubes, passages or channels in said bricks, communicating with the air-tubes in the front water-leg, and said arch having a discharge-cavity and an inclined deflecting-surface at its upper end, substantially as described. 70

4. A locomotive-boiler and its furnace, in combination with an arch composed of refractory bricks suitably supported and separated by non-fusible material, substantially as and for the purpose specified. 75

5. A locomotive-boiler and its furnace, in combination with an arch arranged in said furnace and composed of refractory bricks, and non-fusible material arranged between 80 said bricks, and permitting the removal of certain bricks, to afford access to the boiler flue-sheet, substantially as described.

6. A locomotive-boiler and its furnace, in combination with an arch arranged in said 85 furnace, and composed of refractory bricks, certain of which resemble keystones, and non-fusible material provided in the joints between the latter and the other bricks of the arch, substantially as and for the purpose 90 specified.

7. A locomotive-boiler and its furnace, in combination with an arch composed of outer rows of bricks having beveled inner ends, and a middle row of bricks resembling keystones 95 and adapted to fit between the outer rows of bricks, non-fusible material in the joints between said bricks, and all said bricks being in substantially the same plane, substantially as described. 100

8. A locomotive-boiler and its furnace, in combination with a front arch, in said furnace, composed of a plurality of rows of bricks, the bricks of one row resembling keystones and adapted to be removed without disturbing 105 the other bricks, to permit access to the boiler flue-sheet, substantially as described.

9. A boiler-furnace, its flue-sheet and arch-tubes, in combination with a substantially flat arch composed of refractory bricks resting 110 upon said arch-tubes, and the middle row of bricks being separated from the others and from each other by non-fusible material, substantially as and for the purpose specified.

10. A boiler and its furnace, having a flue-sheet and arch-tubes, in combination with an arch resting upon said arch-tubes and composed of a plurality of channeled bricks and a set of recessed deflector-bricks, the channels of said bricks communicating with the outer air and non-fusible material separating the several bricks, substantially as described. 115

11. A locomotive-boiler and its furnace, flue-sheet and flues, in combination with air-entrance tubes arranged at different elevations in the front water-leg of the boiler, and an arch composed of channeled refractory bricks, forming extensions of said air tubes and the bottom of said arch being lower at the middle than at other points, to avoid in- 125 130

terference with said flues, substantially as described.

12. A locomotive-boiler having the usual furnace, water-legs, flue-sheet and flues, in combination with arch-tubes arranged in the furnace and connecting the front and rear water-legs, air-entrance tubes arranged in the front water-leg at different elevations beneath the cylindrical portion of the boiler, an arch composed of refractory bricks resting upon said arch-tubes and provided with air-channels and deflecting-surfaces, and the bricks of the lower tier in said arch conforming in shape to the positions of respective air-tubes, substantially as described.

13. A locomotive-boiler, containing a furnace and flues and having the usual water-legs, in combination with arch-tubes arranged

in the furnace and communicating with the front water-leg, beneath said flues, air-entrance tubes extending through said front water-leg the middle air-tubes being lower than the others, and a hollow brick arch arranged on said arch-tubes, and having a bottom, middle brick which hangs between said arch-tubes and the air-channels of which communicate with said middle air-tubes, substantially as described.

In testimony whereof we have hereunto set our hands, this 7th day of September, A. D. 1904, in the presence of two witnesses.
